UNITED STATES PATENT OFFICE.

LILLIAN KAUFMANN, OF NEW YORK, N. Y.

HOLDER FOR LADIES' SHIRT-WAISTS.

SPECIFICATION forming part of Letters Patent No. 759,614, dated May 10, 1904.

Application filed February 16, 1904. Serial No. 193,908. (No model.)

To all whom it may concern:

Be it known that I, LILLIAN KAUFMANN, a citizen of the United States, residing in New York, borough of Manhattan, and State of New York, have invented certain new and useful Improvements in Holders for Ladies' Shirt-Waists, of which the following is a specification.

This invention relates to an improved holder for ladies' shirt-waists by means of which the shirt-waist can be held in the desired position over the corset in satisfactory manner without depriving the wearer of the free motion of the arms and without injuring the shirt-waist thereby; and for this purpose the invention consists of a holder for shirt-waists comprising a waistband formed of rigid sections and intermediate elastic sections, the rigid sections being provided with projecting pin-points at their lower edges for piercing the shirt-waist, a plurality of holding-pins suspended from the waistband by elastic straps, and buckle-sections at the front ends of the waistband, one of said buckle-sections being provided with a fastening-pin for holding the shirt-waist to the corset below the buckle.

The invention consists, further, of the buckle-sections provided at their upper ends with forwardly and downwardly bent tapering pointed portions for engaging the front portion of the shirt-waist and holding the waistband of the skirt.

In the accompanying drawings, Figure 1 is a perspective view of my improved holder for ladies' shirt-waists, showing the same in position for use. Fig. 2 is a perspective view of the holder drawn on a larger scale. Figs. 3 and 4 are vertical transverse sections, drawn on a larger scale, respectively, on lines 3 3 and 4 4, Fig. 2. Fig. 5 is a detail perspective view of one form of fastening-pin employed with my improved shirt-waist holder, and Fig. 6 is a side view of the same form of pin as shown in Fig. 5.

Similar letters of reference indicate corresponding parts.

Referring to the drawings, *a* represents the waistband of my improved holder for ladies' shirt-waists. The waistband is made of a number of rigid sections or pin-plates *a'*,

which are preferably made of sheet metal or other suitable material, and intermediate elastic sections *a''*, said elastic sections being either single or double, as desired. The lower edges of the rigid sections are provided with a plurality of pin-points *b*, which pierce the shirt-waist and enter the corset, so as to hold the shirt-waist firmly and properly in position around the waist. The pin-plates *a'* are covered with a suitable textile fabric, preferably of the same color as the color of the intermediate elastic sections *a''*. The front ends of the waistband *a* are formed of looped elastics *a''*, which are attached to the ends of the adjacent pin-plates *a'* and passed through slots *g g'* at the upper ends of the buckle-sections *c c'*. The buckle which is formed by the buckle-sections *c c'* is made in a well-known manner, each section being made of triangular shape, one section being provided with a slot *g* near its meeting edge and the other with an inwardly-bent tongue at its overlapping edge, so as to produce a buckle for connecting the front ends of the waistband of my improved holder. The upper corners *o o'* of the buckle-sections *c c'* are bent forwardly and downwardly, so as to engage the front portions of the shirt-waist and hold the same in the desired position to which the buckle has been adjusted and to hold the waistband of the skirt in position and prevent the same from riding up beyond the buckle. At opposite sides of the waistband *a* and also at the lower ends of the overlapping buckle-sections are arranged fastening-pins *d*, which are made similar to curtain-pins and connected at their upper triangular portion by means of elastic straps *e*, respectively, with two of the pin-plates *a'*, which are provided with slots *l* for attaching the upper ends of the elastic straps *e*, the lower ends being attached to the cross-bar *m* of the fastening-pins. The front fastening-pin is connected by an elastic strap *e* with the overlapping buckle-sections *c c'* and serves for holding the front portion of the shirt-waist in proper position on the corset, while the side pins serve for holding the lower side or hip portions of the shirt-waist also in the required position on the side portions of the corset. The rear pin-plate *a'* is provided at its outer surface

with hooks *h*, so as to make connection with eyes at the rear part of the skirt.

The waistband is attached over the shirt-waist by pressing the pin-points through the 5 shirt-waist, after which the buckle is placed in position at the front portion by means of its fastening-pin, while the side pins are placed in position so as to hold the side portions of the shirt-waist on the corset. In this manner 10 the shirt-waist is securely held in the desired position along its back, sides, and front. Owing to the intermediate elastic connecting- straps of the pin-plates the arms can be moved with comfort and ease, so as to arrange the 15 hair or for other usual purposes without exerting a tearing strain on the shirt-waist, the pin-plates yielding sufficiently for this purpose. By the use of the holder the perfect fitting of the waistband is secured and the desired 20 position of the shirt-waist on the corset is obtained. To produce this result, which is one much wished for by ladies, various devices have been employed heretofore, but without giving satisfaction. My improved 25 holder produces the desired fitting in position of the shirt-waist in a higher degree than the devices heretofore in use and meets thereby in a superior manner the requirements of well-dressed ladies.

30 Having thus described my invention, I claim as new and desire to secure by Letters Patent—

1. A holder for ladies' shirt-waists, consisting of a waistband composed of rigid plates provided with pin-points at their lower edges, 35 intermediate elastic connecting-straps, elastic front end straps, buckle-sections applied to

said elastic front end straps, elastic straps suspended from said rigid pin-plates and the front buckle-sections, and fastening-pins at the sides and front suspended from said elastic 40 straps, substantially as set forth.

2. A holder for ladies' shirt-waists, consisting of rigid pin-plates provided with pin-points at their lower edges, intermediate elastic connecting-straps, elastic front straps, 45 buckle-sections provided with bent-over pointed corners at their upper ends, attached to said elastic front straps, elastic straps suspended from said rigid pin-plates, fastening-pins connected by said straps to the pin-plates, 50 and a front fastening-pin connected by a front strap to the overlapping portion of the buckle-sections, substantially as set forth.

3. In a holder for ladies' shirt-waists, rigid plates provided with slotted portions and with 55 pin-points at their lower edges for piercing and holding the shirt-waist, intermediate elastic connecting-pieces between said pin-plates, elastic front end straps, buckle-sections with slotted portions attached to said front end 60 straps, side and front fastening-pins, elastic straps connecting cross-bars of said fastening-pins with the slotted portions of the side plates and overlapping buckle-sections, substantially as set forth.

In testimony that I claim the foregoing as my invention I have signed my name in presence of two subscribing witnesses.

LILLIAN KAUFMANN.
